UNITED STATES PATENT OFFICE.

WILLIAM PRESTON STALEY, OF SEDALIA, MISSOURI.

PIPE-WRENCH.

1,194,563.

Specification of Letters Patent. Patented Aug. 15, 1916.

Application filed August 6, 1915. Serial No. 44,076.

To all whom it may concern:

Be it known that I, WILLIAM P. STALEY, a citizen of the United States, residing at Sedalia, in the county of Pettis and State of Missouri, have invented a new and useful Pipe-Wrench, of which the following is a specification.

This invention relates to wrenches and more particularly to the adjustable type, designed for gripping and turning pipes, rods, or other circular objects or materials.

An object of this invention is to provide a pipe wrench which is capable of ready and convenient adjustment, and embodying novel automatic locking means.

Another object of this invention is the provision of a pipe wrench which is adapted to securely grip the pipe, or desired material, but which gripping action is limited in order to prevent the crushing of the pipe.

A further object of this invention is to provide a pipe wrench of general improved construction, whereby the device will be simple, durable and inexpensive in construction, as well as practical, serviceable and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

This invention has been illustrated in its preferred embodiment in the accompanying drawing, wherein:

Figure 1 is a side elevation of the improved wrench. Fig. 2 is a fragmental longitudinal sectional view of the gripping end of the wrench. Fig. 3 is a transverse sectional view taken on the line 3—3 of Fig. 2. Fig. 4 is a perspective view of the gripping block.

In carrying out the present invention, there is provided a stationary or fixed shank 1 having a laterally enlarged fixed jaw 2 formed at one end thereof and a manipulat-

ing handle 3 secured to its opposed end. The outer face of the jaw 2 is provided with teeth or serrations 4. An enlargement 5 is formed on the shank 1, adjacent the stationary jaw 2, which enlargement defines an oblique or inclined shoulder 6 at the inner terminal thereof. A yoke 7 is pivotally secured to the enlargement 5, as indicated at 8. The yoke 7 comprises side walls 9 and 60 edge walls 10 and 11, and a transverse partition 12. Opposed rectangular slots 13 are formed in the side wall 9 of the yoke 7, while the edge wall 11 and adjacent portions of the side wall 9 are cut away as 65 shown at 14. The yoke 7 is yieldingly held in predetermined relation with respect to the shank 1, by means of opposed leaf springs 15 and 16, which are secured to the shank 1, by screws or other securing elements 17. The outer or free terminal of the spring 15 resiliently engages the transverse partition 12, while the outer or free terminal of the spring 16 resiliently engages the reduced edge wall 11. 75

Slidably mounted within the yoke 7, is a movable shank 18 having a movable jaw 19 extending perpendicularly from one end thereof. The inner longitudinal edge of the movable shank 18 is provided with teeth 80 or serrations 20, and the inner face of the movable jaw 19 is, also, provided with teeth or serrations 21, which are adapted to cooperate with the teeth 4 of the stationary jaw 2, as will be hereinafter disclosed. In 85 order to lock the movable jaw 19 in operable relation relative to the stationary or fixed jaw 2, there is provided a gripping or ratchet block 22, which has its outer face, or that face which is adjacent the movable shank 18, toothed or serrated as indicated at 23, to operably engage the teeth 20 of the shank 18. Opposed ears or lugs 24 extend laterally from the block 22, and are slidably received by the slots 13. A relatively long 90 leaf spring 25 has one end thereof secured to the stationary shank 1, by means of the screw or other securing element 17, while the opposed terminal of the spring 25 resiliently engages that face of the gripping 95 block 22 which is remote from teeth 23, to normally hold the teeth 23 in engagement. 100

with the teeth 20 of the shank 18. By this arrangement the block 22 is held against longitudinal movement with respect to the yoke 7, owing to the sliding engagement of the 5 lugs or ears 24 with the slot 13, but the block 22 is free to move transversely of the yoke 7, as depicted in the accompanying drawing.

To further insure against the longitudinal 10 movement of the gripping block 22 in the direction of the stress, when the wrench is in use, one end, or that end of the gripping block 22 which is adjacent the shoulder 6, is obliquely or slantingly disposed 15 as indicated at 25, to coöperate with the oblique shoulder 6.

In assembling the improved wrench, the yoke is first secured to the stationary shank 1 by means of the pin 8, and then the 20 springs 15, 16 and 25' are secured to the shank 1, as shown. Now the gripping block 22 is placed in position by disposing its length transversely of the yoke, or so that its length coincides with the length of the 25 slots 13, thereby enabling the block 22 to be inserted into the yoke. After the block 22 has been inserted into the yoke 7, it is turned through an arc of 90 degrees, which allows 30 the ready insertion of the movable shank 18 into the yoke, as illustrated.

In practical use, the movable jaw 19 may be readily moved from the fixed or stationary jaw 2, preparatory to gripping the pipe or rod (not shown) by simply pulling the 35 gripping block 22 against the tension of the spring 25' and away from the serrated movable shank 18, through the instrumentality of the exposed lugs or ears 24, which are readily accessible, to allow their convenient 40 manipulation. After the opposed jaws 2 and 19 are positioned on opposed sides of the pipe and into engagement with the pipe, the wrench will effectively grip and turn the pipe, by simply releasing the ears or lugs 45 24 and moving the wrench handle 3 in the direction of the arrow A. After releasing the ears or lugs 24, the teeth 23 of the gripping block 22 will snap into engagement with teeth 20 of the movable shank 18, therefore 50 by locking the block 22 to the movable shank 18, and, since the oblique shoulder 25 of the block 22 is in engagement with the oblique shoulder 6 of the enlarged portion of the fixed shank, therefore, the entire stress of 55 the gripping and wrenching action is imparted to the enlargement 5 of the fixed shank 1.

It will be observed that any tendency of the gripping block 22 to move away from 60 the movable shank 18, during the gripping wrench action, is obviated by providing the inclined or oblique shoulder 6, because any movement of the block 22 away from the movable shank 18 will cause the block to

move along the oblique shoulder 6 against 65 the direction of the stress of the gripping and wrenching action, which stress or strain is preponderantly in excess of any force which would tend to move the block 22 from engagement with the movable shank 18. 70

Having thus described my invention, what is claimed as new is:—

1. A wrench including a fixed shank; a fixed jaw; an oblique shoulder formed on the fixed shank; a spring controlled yoke 75 pivotally secured to the said fixed shank; a movable shank slidably mounted in the said yoke; a movable jaw carried by the movable shank; a gripping block slidably mounted in the said yoke; and an oblique shoulder 80 formed on the said gripping block and adapted to operably engage the oblique shoulder formed on the fixed shank.

2. A wrench including, a fixed shank; an enlargement formed at the outer end of the 85 said fixed shank; an obliquely disposed shoulder formed on the said enlargement; a serrated fixed jaw carried by the said enlargement; a spring controlled yoke pivotally secured to the said enlargement; a serrated movable shank longitudinally slidable within the said yoke; a serrated movable 90 jaw extending transversely from the said movable shank; a spring actuated serrated gripping block slidably mounted in the said 95 yoke and adapted to operatively engage the said serrated movable shank; an oblique shoulder formed on the said gripping block and adapted to slidably engage the oblique shoulder of the said enlargement. 100

3. A wrench including a fixed shank; an oblique shoulder formed in the said shank; a fixed jaw carried by the said fixed shank; teeth formed in the outer face of the said fixed jaw; a yoke pivotally secured to the 105 fixed shank, said yoke comprising opposed side walls having opposed rectangular slots formed therein, opposed edge walls, one of which is reduced, and a transverse partition formed in the yoke and extending from the 110 opposed side walls; opposed flat springs having one end secured to the said fixed shank, the free end of one of said springs resiliently engaging the said reduced edge wall, while the free end of the remaining 115 spring resiliently engages the said transverse partition, said springs adapted to normally hold the yoke in predetermined relation with respect to the said fixed shank; a movable shank slidably mounted in the said 120 shank; teeth formed on the said shank; a movable jaw extending from the said movable shank; teeth formed on the inner face of the said movable jaw and adapted to co- 125 operate with the teeth formed in the said fixed jaw; a gripping block slidably mounted in the said yoke; teeth formed on the face of said block and adapted to operably

engage the teeth formed on said movable shank; an ear extending laterally from each side of the said block and adapted to extend through and slidably engage the said rectangular slots; an oblique shoulder formed on the said block and adapted to slidably engage the oblique shoulder formed on the said fixed shank; and a leaf spring secured to the said fixed shank, the free end of which **10** spring is adapted to resiliently engage the

gripping block to normally press the teeth of said block into engagement with the teeth of the said movable shank.

In testimony that I claim the foregoing as my own, I have hereto affixed my signature in the presence of two witnesses.

WILLIAM PRESTON STALEY.
